SERVING TRAY

Hugh William Lindsay, Gastonia, N. C.

Application March 13, 1934, Serial No. 715,339

2 Claims. (Cl. 224—48)

This invention relates to serving trays and more particularly to a sanitary means for sealing containers which are supported in the tray so as to prevent spilling of the contents thereof.

5 An object of this invention is to provide in a serving tray means whereby cups or other containers, which are supported in the tray, will be covered by means of a sanitary cover which is held in tight position by means of a plate detachably carried by the tray structure.

Another object of this invention is to provide a tray structure of this kind which is adapted to be used in the serving of drinks at roadside places or other places where the drinks are carried for a distance from the point of serving and which includes means to prevent the contents of the containers from being contaminated.

The above and various other objects and advantages of this invention will in part be described and in part be understood from the following detailed description of the present preferred embodiment, the same being illustrated in the accompanying drawing wherein:

Figure 1 is a detail perspective view of a device constructed according to the preferred embodiment of this invention.

Figure 2 is a sectional view taken on the line 2—2 of Figure 1.

Figure 3 is a fragmentary plan view of the clamping plate for the sanitary sealing member for the containers supported in the tray.

Referring to the drawing wherein like numerals of reference designate corresponding parts throughout the several views, the numeral 10 designates generally a tray structure comprising a base 11 and an article supporting rack 12 which is secured to the base 11 by a standard or post 13. The rack 12 comprises a plate 14 provided with a plurality of apertures, each defined by a depending inverted frusto-conical member 15 within which a cup or liquid holding member 16 is adapted to engage. Preferably, the cups or liquid holding members 16 are of a size such that the lower portion thereof will project below the bottom of the depending members 15. The central portion of the plate 14 has a chamber 17 secured thereto and extending therebelow. This chamber 17 is adapted to receive articles such as packages of merchandise in the form of cigarettes or may receive pieces of ice. The top of the standard 13 is secured to the central portion of the bottom of the chamber or well 17.

A substantially U-shaped handle or bail 18 is secured to the plate 14, and this bail 18 has on one leg 19 thereof, a match chamber or com-

partment 20. This member 20 may be of sufficient depth to hold straws or like articles.

A cover plate 21 provided with an elongated bail receiving slot 22 is adapted to engage the top of the cups or containers 16. This plate 21 is preferably constructed of relatively rigid material and the slot 22 terminates at one end in a rounded opening 23 which engages about the vertically opening compartment 20.

Another object of this invention is to provide a tray structure of this kind which is adapted to be used in the serving of drinks at roadside places or other places where the drinks are carried for a distance from the point of serving and which includes means to prevent the contents of the containers from being contaminated.

In order to hold the cover plate 21 in a tight position on top of the cups or containers 16 and to also tightly clamp the cups 16 within the cup receiving members 15, I have provided a pair of depending lugs 25 and 26, which are carried by the cover plate 21. The lug 25 engages against one end of the bail 18 and preferably engages against the leg 18 of the bail, whereas the lug 26 engages against the outer side of the container 20. The leg 18 at a desired point intermediate its length, is provided on the outside thereof with a projection 27, and on the lug 25 is provided with a detent 28 within which the projection 27 is received. In like manner, the container 20 has a projection 29, which is engaged by a detent 30 carried by the lug 26. Through the use of these lugs 25 and 26 and the projections 27 and 29, the cover plate 21 is clamped and firmly held against the tops of the cups 16 so that the contents of the cups will not spill while the tray is being carried.

In the use of the tray structure herein disclosed, the containers or cups 16 may be inserted in the openings provided in the plate 14, and when the desired number of cups have been placed in the rack 12, the napkin 24 may be slipped over the bail. The cover plate 21 is then slipped over the bail and moved inwardly thereof until the lugs 25 and 26 engage the projections 27 and 29, respectively. When the cover plate 21 is in position, a considerable portion of the bail will project thereabove and the top of the match compartment 20 will project thereabove. The tray can then be carried to the customer and during the carrying of the tray, it will be obvious that the contents of the cups 16 will not spill out. The receptacle 17 may have either ice, cigarettes or any other article disposed therein, so that the device may be used for the serving of drinks and other articles.

55

What is claimed is:—

1. In a serving tray structure including an article supporting rack, a bail carried by the rack, a cover plate having a slot to receive said bail, depending recessed yieldable clamping members integral with the plate and disposed at opposite ends of the slot, means fixedly carried by the bail and engageable within the recess of each member to releasably hold the plate in operative position.
2. In a serving tray structure including an ar-

5 ticle supporting rack and a bail carried by the rack, a cover plate having an elongated slot therein to loosely engage about the bail, depending recessed yieldable clamping members integral with the plate and disposed at opposite ends of the slot, means fixed to the bail engageable within the recess of each member to releasably hold the bail in operative position, and a fabric sheet disposed between the plate and the tops of articles disposed in the supporting rack.
